UNITED STATES PATENT OFFICE.

JOSEF MUTHIERR, OF NUREMBERG, GERMANY.

CARTRIDGE.

SPECIFICATION forming part of Letters Patent No. 616,721, dated December 27, 1898.

Application filed April 5, 1898. Serial No. 676,510. (No model.)

To all whom it may concern:

Be it known that I, JOSEF MUTHIERR, a subject of the King of Bavaria, and a resident of Nuremberg, Bavaria, Germany, have invented new and useful Improvements in Cartridges, (for which I have applied for patents in Austria and Hungary, dated January 22, 1898,) of which the following is a full, clear, and exact description.

10 My invention relates to cartridges adapted to central firing, and has for its object to provide means whereby said cartridges may have only a priming-powder, such as used in the well-known "Flobert" ball-caps.

15 To this end my invention consists in the particular features of construction hereinafter described, and illustrated in the accompanying drawings, in which similar characters of reference indicate corresponding parts in both the views.

Figure 1 is a sectional view of the improved cartridge; and Fig. 2 is a similar view of the same, taken at right angles to that shown in Fig. 1.

20 *a* is the shell of the cartridge, in the interior of which the priming-powder *b* is located on the bottom of the shell *a*. Said priming-

powder *b* is covered by a layer or disk *d* of any suitable material, and across the same there is arranged a pin or cross-stay *c*, being secured in the shell *a* by pressure, which forms a shoulder in the shell, said shoulder bearing on the ends of the bar to hold the same. The upper end of the cartridge-shell *a* bears the ball *c*, which is inserted in a well-known manner. The pin or cross-stay *c* serves as a beater or anvil for firing the priming-powder *b*, which may be done by a central stroke on the rear side of the cartridge.

Having thus described my invention, I claim as new and desire to secure by Letters Patent—

A cartridge having a shoulder formed therein, an explosive in the base of the cartridge, a disk bearing on the explosive, and a bar located in the cartridge and extending transversely thereto and having its ends bearing on the shoulder whereby to hold the bar in place, the bar bearing on the disk and forming an anvil on which to fire the explosive.

JOSEF MUTHIERR.
